APPLIANCE TO HOLD DENTAL RUBBER DAM

Harry G. Greene, 1737 W. Howard St.,
Chicago, Ill. 60626

Filed Jan. 15, 1968, Ser. No. 10,159

Term of patent 14 years

(Cl. D24—1)

FIG. 1 is a top plan view of my appliance;

FIG. 2 is an elevational view taken on the lower side of FIG. 1;

FIG. 3 is an elevational view taken on the left side of FIG. 1;

FIG. 4 is a bottom plan view of FIG. 1;

FIG. 5 is a plan view of my appliance in one of its operative positions, and

FIG. 6 is a plan view of my appliance in another operative position.

I claim:

The ornamental design for an appliance to hold dental rubber dam, substantially as shown.
